FLOW CONTROL DEVICE

Robert R. Dahl and Howard L. Erickson, Chicago, Ill., assignors to The Dole Valve Company, Chicago, Ill., a corporation of Illinois

Application May 19, 1955, Serial No. 509,549

6 Claims. (Cl. 138—45)

This invention relates to improvements in flow control devices for maintaining a substantially uniform rate of flow of fluid over a wide range of pressure variations.

A principal object of our invention is to provide an improved form of flow control device so arranged as to effectively operate under higher pressure and delivery volume ranges than have heretofore been considered possible.

A further object of our invention is to improve upon the annular flow control devices heretofore in use by molding a stabilizing ring within the flow control device to prevent distortion thereof, to accommodate the capacity of the flow control device to be increased without an increase in the outside diameter thereof and the size of the casing therefor.

Another object of the invention is to provide a flow control device in the form of a resilient annular flow control member for providing a uniform flow rate over a wide range of pressure variations, in which buckling, distortion or collapse of the flow control annulus is prevented, to accommodate the device to operate at far higher pressure and delivery volume ranges than have heretofore been considered possible.

Still another object of our invention is to provide a novel and improved form of flow control device in the form of a resilient flow control annulus in which the control of the flow of fluid is obtained by flexure of the member to vary the area of the flow passageway leading therethrough as the pressure varies, and in which the annulus is stabilized to effect uniform restriction of the flow orifice through the annulus without distortion of the annulus.

A still further object of our invention is to provide a simpler and more efficient form of flow control device in the form of a resilient annulus, in which the flexure or bending action of the annulus for the control of the flow is substantially unaffected and distortion of the annulus is prevented by the provision of a metallic insert within the annulus concentric with the center of the orifice leading therethrough and spaced a predetermined distance from the downstream side of the annulus, to stabilize the annulus against distortion without substantially affecting the bending and flow control action thereof.

Still another object of our invention is to provide a novel and efficient form of flow control device arranged to more accurately control the flow than formerly, particularly at high pressure and volume ranges, by contouring the downstream face of the annulus in the form of the frustum of a flat cone, accommodating the flow of the material of the annulus along the seat therefore upon increases of pressure, and by providing a thin metallic insert in the annulus coaxial with the center of the flow orifice therethrough and closer to the downstream face of the annulus than the upstream face thereof.

These and other objects of our invention will appear from time to time as the following specification proceeds

2

and with reference to the accompanying drawings wherein:

Figure 1 is an end view of a flow control device and casing constructed in accordance with our invention looking at the casing from the upstream end thereof.

Figure 2 is a longitudinal sectional view taken substantially along line II-II of Figure 1, showing the flow control device in an unstressed condition;

Figure 3 is a fragmentary sectional view somewhat similar to Figure 2, but showing the flow control device in an extreme flexed condition, effected by the pressure of the fluid acting thereon; and

Figure 4 is a plan view of the flow control member looking at the member from the downstream face thereof.

In the embodiment of our invention illustrated in the drawing, we have shown a coupling or casing 10 which may be connected in a water line or in association with either the intake or discharge end of a valve or like device. The casing 10 has a passageway 11 leading thereto and terminating into a shoulder 12 intermediate the ends of said casing against which rests a seat 13, which may be pressed thereagainst. The seat 13 is shown as being in the form of an annulus having a central orifice 15 leading therethrough and forming a seat for a resilient flow control device or annulus 16, having a central orifice 17 leading therethrough and of a smaller diameter than the orifice 15, to accommodate the free flow of fluid through the orifice 15 in all positions of flexure of the flow control device 16 along the seat 13.

On the downstream side from the seat 13 and the shoulder 12 is a passageway 19 of larger diameter than the passageway 15 leading through the seat 13 and terminating into a frusto conical passageway 20 terminating in an outlet passageway 21 from the casing or coupling 10.

Seated within the passageway 11 on the upstream side of the flow control device 16 is a retainer ring 23 loosely retaining the flow control device 16 to the casing or coupling 10 in position to engage the seat 13 and bend inwardly into engagement therewith upon increases in pressure on said flow control device. The retainer ring 23 is spaced from the flow control device 16 a distance sufficient to accommodate a certain limited freedom of movement of said flow control device.

The flow control device 16 controls the flow of fluid under pressure by the reduction in the cross-sectional area of its orifice 17, upon increases in pressure thereon, on the same general principles as have been disclosed in Patent No. 2,389,134, which issued to Clyde A. Brown on November 20, 1945. The flow control device 16 may be made from a resilient or elastic material, such as rubber or one of the well known substitutes for rubber, such as neoprene, and the like, so as to be readily flexible in a downstream direction upon increases in pressure of the fluid acting thereon.

The upstream face of the flow control device 16 is shown as being flat and as having a uniformly curved inner corner 24 leading to the orifice 17 and providing a uniform relatively smooth orifice for all degrees of bending or flexure of said flow control device as the pressures vary. The inner wall of the flow control device is shown as being cylindrical when the device is in an unflexed condition. The wall, however, may taper outwardly toward the downstream side of the flow control device at a slight angle if desired. The flow control device 16 also has an outer wall 25 spaced inwardly from the wall of the passageway 11 a distance sufficient to accommodate free bending of said control device under the pressure of fluid acting thereon, when in place within the passageway 11.

The downstream face of the flow control device 16

is shown as being of a concave form and contoured inwardly to form a concave face 26, generally frusto-conical in form and extending inwardly from a location close to the outer margin of the flow control device and terminating into a plane face parallel to the upstream face of the flow control device, which extends to the margin of the central orifice 17.

Recessed within the flow control device 16 and coaxial with the center of the orifice 17 thereof is a stabilizing device 30, herein shown as being a relatively thin metal ring or sleeve which may be molded within the flow control device 16 upon the molding thereof.

During the operation of molding the flow control device 16, the metal insert 30 is supported on a plurality of pins (not shown) which may be four in number. At the end of the molding operation the pins are removed leaving the holes 31. These holes have no effect on the control of the flow of fluid through the orifice 17.

The stabilizing insert 30 is shown as being located closer to the downstream face of the flow control device 16 than the upstream face thereof, and may be located at the various positions along said flow control device, but preferably should be spaced closer to the downstream face of the flow control device than the upstream face thereof and should be located on the downstream half of the flow control device so as to have no substantial effect on the bending and flow control action thereof.

While the stabilizing device is shown as being in the form of a solid ring, it should be understood that the ring need not be solid but may be split if desired. The ring further should be as narrow as molding operating pressures will permit and while larger than the inside diameter of the orifice 15 should come as close to the inside diameter of said orifice as practical, commensurate with manufacturing and functional requirements.

It may be seen from Figure 2, that as fluid under pressure acts on the flow control device 16, the device will flex in the direction of the flow of fluid through the orifice 17 and gradually reduce the flow area thereof, the frusto-conical downstream face 26 moving radially inwardly along the face of the seat 13.

It may further be seen that a simple and improved form of flow control device has been provided which is particularly suited for the control of fluid at relatively high pressures, and that high pressure operation is attained without distortion of the flow control device by stabilizing without substantially effecting the bending movement and flow control action thereof as the pressures on the flow control device increase; so as to hold the orifice from distortion and prevent buckling of the flow control device and thus increase the life thereof.

It may still further be seen that stabilization of the flow control device is attained without substantially effecting the bending and flow control action thereof by the use of a thin insert which may be metal, and by the positioning of this thin insert in such relation with respect to the upstream face of the flow control device as to have no substantial effect on the reduction in cross-sectional area of the orifice as pressures thereon increase and to hold the flow control device from distortion under extreme high pressure conditions.

It may also be seen that by the inclusion of the metal insert, a flow control of a given diameter may have a larger orifice than heretofore, with the result that the housing for the flow control may be smaller and less expensive for a given volume of fluid than formerly.

It may further be seen that with the stabilized flow control device of our invention, that the ratio between the diameter of the central orifice of the flow control device and the outside diameter thereof may be increased from former flow control devices so as to accommodate the flow control device to efficiently operate under far higher pressure and rate of flow conditions than have

heretofore been considered possible with such flow controls.

It should further be understood that the term distortion as used herein is intended to be construed as buckling or collapsing of the orifice into a non-circular shape.

It may still further be seen that the flow control characteristics of the flow control may be varied by changing the relative size of the insert or varying its position with respect to the upstream side of the flow control member.

It will be understood that modifications and variations in the present invention may be effected without departing from the spirit and scope of the novel concepts thereof.

We claim as our invention:

1. A fluid flow control device for maintaining a substantially uniform delivery rate over a wide range of pressure variations comprising a casing having a passageway leading therethrough, a flat seat in said passageway facing the upstream side thereof, a resilient annular flow control device loosely carried in said passageway and seating against said seat upon the flow of fluid therethrough, the inner margin of said flow control device defining a central fluid flow orifice deformable upon increases in pressure to restrict the cross-sectional area thereof, and means stabilizing said flow control device upon increases in pressure thereon and effecting a uniform restriction of said orifice throughout the full control range thereof, comprising a thin metal ring carried within said flow control device concentric with and relatively close to the orifice thereof, and spaced axially inwardly from the downstream face of said flow control device a distance less than half the thickness of said flow control device.

2. In a fluid flow control device for maintaining a substantially uniform delivery rate over a wide variation in pressures, a casing having a passageway leading therethrough, a flat seat in said passageway facing the upstream side thereof, a resilient annular flow control device in said passageway seating against said seat upon the flow of fluid therethrough, said flow control device having a generally frusto-conical inwardly contoured downstream face, facing said seat and engaging the same adjacent the outer margins thereof upon normal pressure conditions and flexing downwardly and radially inwardly into engagement with said seat upon increases in pressure thereon to reduce the cross-sectional area thereof, and means stabilizing deformation of said flow control device and effecting a uniform reduction in cross-sectional area of said orifice throughout the full range of flow control thereof comprising a thin metallic ring recessed within said flow control device in radial outwardly spaced relation with respect to said orifice and concentric therewith, and spaced axially closer to the downstream side of said flow control device than to the upstream side thereof.

3. In a fluid flow control device for maintaining a substantially uniform delivery rate over a wide variation in pressures, a casing having a passageway leading therethrough, a flat seat in said passageway facing the upstream side thereof, a resilient annular flow control device in said passageway seating against said seat upon the flow of fluid therethrough, said flow control device having a generally frusto-conical inwardly contoured downstream face, facing said seat and engaging the same adjacent the outer margins thereof upon normal pressure conditions and flexing downwardly and radially inwardly into engagement with said seat upon increases in pressure thereon to reduce the cross-sectional area thereof, and means stabilizing said flow control device and effecting a uniform reduction in cross-sectional area of said orifice throughout the full range of flow control thereof, comprising a thin metal ring molded within said flow control device concentric with the orifice thereof and

spaced relatively close to said orifice but radially outwardly therefrom and axially inwardly from the downstream face of said flow control device a distance less than the half the thickness thereof.

4. A fluid flow control device comprising a casing having a passageway leading therethrough, a flat seat in said passageway facing the upstream side thereof, a resilient annular flow control device loosely carried in said passageway and seating against said seat, the inner margin of said flow control device defining a central flow orifice deformable upon increases in pressure on said flow control device to reduce the cross-sectional area of said orifice, and a stabilizing ring concentric with the center of said orifice and spaced radially outwardly therefrom closer to downstream than the upstream side thereof for preventing distortion of said flow control device upon increases of pressure thereon and maintaining a uniformly restricted orifice in the extreme deflected positions thereof.

5. A fluid flow control device comprising a casing having a passageway leading therethrough, a flat seat in said passageway facing the upstream side thereof, a resilient annular flow control device loosely carried in said passageway and seating against said seat upon the flow of fluid therethrough, the inner margin of said flow control device defining a central fluid flow orifice decreasing in cross-sectional area upon increases in pressure on the upstream face of said flow control device, and a metal stabilizing ring molded within said flow control device concentric with the center of said orifice and closer to the downstream face of said flow control device than the upstream face thereof, for preventing distortion of said flow control device and maintaining the contour of said flow control device and maintaining the contour of said orifice uniform in the extreme restricted positions of said orifice uniform in the extreme restricted positions

thereof and thereby enabling the flow capacity of said flow control device to be increased without an increase in the size of the casing therefor.

6. A fluid flow control device comprising a casing having a passageway leading therethrough, a flat seat in said passageway facing the upstream side thereof, a resilient annular flow control device loosely carried in said passageway and arranged to seat against said seat upon predetermined upstream pressure conditions, the inner margin of said flow control device defining a central fluid flow orifice decreasing in cross-sectional area upon increases in pressure on the upstream face of said flow control device, and a metal stabilizing ring molded within said flow control device concentric with the center of said orifice being located relatively close to the central fluid flow orifice and closer to the downstream face of said flow control device than the upstream face thereof, for preventing distortion of said flow control device and maintaining the contour of said orifice uniform in the extreme restricted positions thereof and thereby enabling the flow capacity of said flow control device to be increased without an increase in the size of the casing therefor.
